UNITED STATES PATENT OFFICE.

JOSEPH A. MORTON, OF BROOKLYN, NEW YORK, ASSIGNOR TO BENJAMIN GIBBS, OF ARDMORE, PENNSYLVANIA.

UNION UNDERGARMENT.

Application filed July 23, 1927. Serial No. 207,856.

This invention relates to union undergarments, particularly those intended to be worn by men, and is an improvement on the union undergarment set forth and claimed in the 5 patent to Benjamin Gibbs, #1,088,338, dated February 24, 1914.

In the union undergarment of the aforesaid patent, the seat flaps extend all the way up to the seam connecting the body of the 10 garment to the split elastic belt and they are also connected to the split belt.

When the Gibbs undergarment is made of knitted material, the construction of Patent 1,088,338 very satisfactorily serves its intended purpose but when the garment is of 15 woven material, for instance, nainsook, it has been found that there is a tendency for the garment to become uncomfortable in the crotch because the seat flaps are, in that instance, inelastically supported.

The object of the present invention is to provide improvements, particularly adapting the undergarment of patent 1,088,338 to be made up of woven material, for 25 instance, nainsook, in so far as the body, legs, and seat flaps are concerned, provision being made to elastically support the flaps in a novel manner by overlapping the ends of the split belt thereby to increase the size 30 of the seat opening, and reinforcing that part of the split elastic belt which directly supports the seat flaps, but without causing any tendency toward discomfort at the crotch of the garment. My present improvements retain the feature of the fundamental 35 elastic split-belt which characterizes the construction of the aforesaid patent, and the advantages of the patented construction but eliminate discomfort in the crotch of the garment when it is made of woven material. 40 This improved result is due to the elastic support of the seat flaps. I also provide an improved snubbing flap-supporting device which allows adequate "stretch" as between 45 the flaps and the body of the garment and yet prevents distortion of the split belt, particularly where its ends overlap, or sagging of either the legs or the flaps or the crotch part of the garment.

50 My object is accomplished by connecting the upper end part of the underseat flap to one end part of the elastic split belt; also, by connecting the upper end part of the outer seat flap to the other end part of the split belt, overlapping the "split" ends of

the elastic belt at the rear of the garment and continuing the last named upper end part of the outer flap in the form of a "snubber" of elastic knitted material having its wales extending in a general up and down 60 direction, that is, cross wise in relation to the elastic belt, and connecting said snubber to the body of the garment.

The snubber has a certain degree of looseness, enabling it to stretch in the direction of its length that is, in a general up and down direction so that it will elastically support the seat flap and will also prevent undue stretching or sagging of the split elastic belt, particularly where the "split" ends of 70 said belt overlap. The overlapped ends of the split elastic belt mutually reinforce each other and, while affording adequate "stretch", prevent undue sagging. If, however, undue strain is put upon them, the snubber will prevent them from becoming unduly stretched and losing their elasticity.

I am aware that modifications may be resorted to in carrying out the present improvements and it is not intended to limit 80 the invention to the details of the present disclosure as the objects of the invention may be attained if the construction is modified in some particulars.

In the accompanying drawings:

Figure 1 is a front view of the undergarment, opened out, and with the under flap folded back to better show the split-belt and the upper ends of the flaps;

Figure 2 is a rear view of the undergarment; and

Figure 3 is a detail perspective view showing the improved split-belt and snubber construction at the back of the undergarment.

The body 1 and the legs 2 and 3, as also 95 the under seat flap 4 and the outer seat flap 5 are of woven material, for instance, nainsook.

The arrangement of the flaps 4 and 5 in respect to their overlying position, is the 100 same as set forth in the Gibbs Patent #1,088,338.

The split elastic belt, preferably made of knitted elastic material having its wales running cross wise of the garment, is composed 105 of the parts 6 and 7. This split belt while fundamentally of the same construction as set forth and claimed in the Gibbs Patent #1,088,338, having its ends disconnected at the rear of the garment as clearly shown in 110

Figure 3, has its "split" ends arranged in an improved manner, as more particularly shown in said figure. The ends of the parts 6 and 7 overlap each other, thereby mutually reinforcing each other at the central part of the back of the belt, thus minimizing any tendency to become unduly stretched under strain.

The respective seat flaps 4, 5 are connected 10 by seams 8 to the legs 2, 3 and the garment has a crotch 9, as usual.

Any suitable fastening means, such as a button and button hole 10 may be provided to fasten the seat flaps 4 and 5 together as 15 shown in Figure 2.

The under seat flap 4 has its upper end connected to the split belt section 6 as shown at 11 but it may continue further up on the belt section 6 than as illustrated in Figure 3.

20 The upper end part of the outer seat flap 5 is continued in the form of an elastic, stretchable "snubber" 12 comprising a piece of knitted material whose wales run in a general up and down direction, that is, in 25 the direction of the length of the flaps 4 and 5, and crosswise of the split belt. The snubber 12 is stitched at 13 to the upper end part of the seat flap 5, being thereby connected to the end part of the split belt section 7. The snubber 12 is also stitched at 30 14 to the body 1 but may be also stitched to the belt section 7. This arrangement of the snubber locates it in overlying relationship to the overlapped ends of the sections 35 6 and 7 of the split belt for the purpose of preventing said overlapped ends from becoming unduly stretched if subjected to undue strain. The snubber 12 is preferably of greater length than the normal width of 40 the split belt 6, 7 so that the split belt may stretch or widen in a crosswise direction to a sufficient extent to render the garment entirely comfortable at all times but this snubber limits the up and down stretching of the 45 split belt so that it cannot unduly stretch or assume a permanent sag from undue stretching.

My improvements enable the split belt

construction of the Gibbs Patent 1,088,338 to be used in connection with relatively in- 50 elastic body, legs and seat flaps such as those of nainsook, a material, which at the present time, is greatly preferred to knitted material in men's union undergarments, inasmuch as these improvements enable the wearer to 55 assume different postures without experiencing any uncomfortable "drawing" action on the part of the garment, because the split elastic belt is employed and yet it is prevented from sagging by reason of the em- 60 ployment of the snubber 12.

What I claim is:

1. A union undergarment having an elastic belt which is split at the back of the garment and there provided with elastic overlapping ends, said belt connecting the body and legs of the undergarment. 65

2. A union undergarment having an elastic belt which is split at the back of the garment and there provided with elastic overlapping ends, said belt connecting the body and legs of the undergarment, and an elastic snubber connecting the body and legs of the undergarment where the ends of elastic belt overlap. 70

3. A union undergarment comprising a body, legs, seat flaps, and an elastic belt connected to the body, the legs, and the upper parts of the seat flaps, said belt having elastic overlapping disconnected ends at the back 75 of the garment which extend the seat opening up to the body. 80

4. A union undergarment comprising a body, legs, seat flaps, and an elastic belt connected to the body, the legs, and the upper parts of the seat flaps, said belt having elastic overlapping disconnected ends at the back of the garment which extend the seat opening up to the body, and an elastic "snubber" connecting the body and legs of the 85 undergarment where the ends of the elastic belt overlap. 90

In testimony whereof I hereto affix my signature.

JOSEPH A. MORTON.
